UNITED STATES PATENT OFFICE.

GEORGE BENJAMIN HOWLAND, OF PONTIAC, ILLINOIS, ASSIGNOR TO
FRANCIS N. SMITH, OF SAME PLACE.

BOARD-RULE.

SPECIFICATION forming part of Letters Patent No. 469,363, dated February 23, 1892.

Application filed March 30, 1891. Serial No. 387,041. (No model.)

To all whom it may concern:

Be it known that I, GEORGE BENJAMIN HOWLAND, a citizen of the United States, residing at Pontiac, in the county of Livingston and State of Illinois, have invented a new and useful Register for Board-Rules, of which the following is a specification.

My invention relates to improvements in board-rules used in measuring lumber; and the object of my invention is to provide a registering device whereby the person measuring lumber is enabled to conveniently register each hundred feet as measured, thereby obviating the necessity of keeping the number in mind or of resorting to the usual and more inconvenient methods of recording the same. This I accomplish by the mechanism illustrated in the accompanying drawings, in which—

Figure 1 is a perspective view of a handle for a board-rule, showing the registering device applied thereto, which may be attached to a rule in any convenient way. Fig. 2 is a bottom view of the device; Fig. 3, same view with the frame G removed in order to display more clearly the working parts. Fig. 4 is an inverted vertical section. Fig. 5 is a perspective of under side of the dial-plate. Fig. 6 is a top view of the dial-plate.

Similar letters refer to similar parts throughout the several views.

By grasping the shaft at F and turning it to the left, the pawl C striking a tooth of the flange B, the dial-plate is made to rotate sufficiently to bring the next figure on the plate 35 directly under the aperture in the cap H. The stud K in opening J limits the movement of the shaft A, and the spring or pawl E prevents any backward movement of the plate. Spring D brings the shaft, with pawl 40 C, back to its former position ready for a repetition of the movement whenever desired.

It will be noticed that the pawl C and spring D are formed of one piece of metal, (usually spring-wire,) which passes through 45 and around the shaft A, to which it is firmly attached by means of a key.

What I claim as my invention, and desire to secure by Letters Patent, is—

In a board-rule, the combination, with handle J, of a registering device consisting of a dial-plate M, with its serrated flange B, pawls C and E, spring D, stop K, cap H, and shaft A, substantially as set forth.

GEORGE BENJAMIN HOWLAND.
